UNITED STATES PATENT OFFICE

2,564,415

ELECTRIC STEAM IRON

Alfred Wild, Milwaukee, Wis.; Elizabeth Wild,
executrix of said Alfred Wild, deceased

Application July 5, 1945, Serial No. 603,355

3 Claims. (Cl. 38—77)

1

This invention relates to improvements in electric steam irons of the character in which the same electric resistance element supplies heat both for the generation of steam and to the smoothing surface of the iron.

It is one object of the present invention to provide an electric steam iron in which a water container and steam generator is separate from the other major portions of the combination and is readily removable and replaceable therein.

Another object of the invention is to provide an electric steam iron in which a unitary structure cooperates with the water container and acts as a water separator, a steam conduit, a connector and spacer for other parts, and a pressure relief means for the steam generator.

Another object of the invention is to provide an electric steam iron in which a single element acts both as a steam superheater and as a steam distributor to the material to be ironed.

Another object of the invention is to provide an electric steam iron in which all operating elements of the iron are enclosed in a shell so related to such operating elements as to minimize the flow of heat thereto from such elements.

Another object of the invention is to provide a steam electric iron with a handle which encloses parts of the operating elements and is so mounted on the shell as to minimize the flow of heat thereto from the shell.

A further object of the invention is to provide an electric steam iron which is divided into a plurality of sub-assemblies so arranged and interrelated as to be readily assembled and disassembled in a predetermined sequence of operations.

Another object of the invention is to provide a readily adjustable connection between the thermostat controlling stem of an electric iron and a thumb-wheel for varying the setting of the thermostat during operation of the iron.

And a further object of the invention is to provide an electric steam iron which is more efficient, more comfortable to the user, and more durable and more readily kept in effective condition than the irons known heretofore.

Objects and advantages other than those above set forth will be apparent from the following description when read in connection with the accompanying drawings, in which:

Fig. 1 is a top plan view with a portion of the handle and shell broken away to show the structure of one of the sub-assemblies of the iron;

2

Fig. 2 is a vertical cross section taken substantially on a central longitudinal plane but showing the handle in elevation except for a portion thereof broken away;

5 Fig. 3 is a partial view looking at the bottom of the sole plate;

Fig. 4 is a transverse vertical section taken on the plane IV—IV of Fig. 2;

Fig. 5 is a transverse section taken on the plane 10 V—V of Fig. 2;

Fig. 6 is a vertical section taken on the plane VI—VI of Fig. 2;

Fig. 7 is a partial top plan of the water container and steam generator;

15 Fig. 8 is a partial top plan of the iron on an enlarged scale with a portion thereof in section on the horizontal plane of broken line VIII—VIII of Fig. 9;

Fig. 9 is a fragmentary view partially in elevation and partially in vertical section, and on an enlarged scale, of the shell enclosed space toward the rear of the iron and of the contents of such space;

Fig. 10 is a section taken on the plane X—X 20 of Fig. 9 to illustrate the connection between the thermostat stem and thumb-wheel and its relation to the handle structure;

Fig. 11 is an enlarged detailed view of portions of the structure of Fig. 10;

30 Fig. 12 is a horizontal sectional view of the spacer portion of one sub-assembly of the iron, taken on the plane XII—XII of Fig. 2;

Fig. 13 is an elevation of the terminal block for the various electrical connections within the 35 iron;

Fig. 14 is a cross section taken on the vertical plane XIV—XIV of Fig. 13 and showing the terminal block with one electric conductor connected therewith;

40 Fig. 15 is an elevation of the electrical insulating and heat-resistive portion of the terminal block;

Fig. 16 is a bottom view of a modified form of the steam super-heater and distributor;

45 Fig. 17 is a vertical sectional view taken on the plane XVII—XVII of Fig. 16;

Fig. 18 is a vertical section through a modified form of the water separator portion of one sub-assembly of the structure; and

50 Fig. 19 is a horizontal sectional view taken on the plane XIX—XIX of Fig. 18.

Referring more particularly to the drawings, the reference numeral 20 designates the generally triangular sole plate of an iron in which is embedded an electrical heating element 21. The

sole plate is formed with sides sloping at any desired angle and which are partially rabbetted along the upper edge, as indicated at 22, such rabbet extending along all three sides of the plate but being interrupted at intervals by pads 23. A recess, preferably of frusto-conical shape, is formed in the sole plate of the iron from the bottom or smoothing surface thereof and an aperture is made through the sole plate into the recess and is interiorly threaded, such recess and aperture receiving other elements of the assembly to be described.

A water container and steam generator 28 is formed as a separate element of the combination and is of such size that the bottom thereof seats on that portion of the sole plate within the area defined by the inner edge of the rabbet 22. The other surfaces of the water container are shaped to conform to substantially the desired outer contour of the iron and are of such dimensions that approximately a pint of water may be placed in the container to fill the container up to the water level marked. Water is placed in the container 28 through a filling neck 29 exteriorly threaded to receive a cap 30 sealed to the end of the neck by way of a gasket 31. The upper portion of the water container 28 is depressed (see Fig. 7) to form a specially shaped socket 32 with a similarly shaped opening 33 in the bottom thereof and defined by a flange 34. The container 28 is also apertured through the bottom thereof for registry with the hole through the sole plate when the container is in its assembled position thereon. The water container is preferably made of a good heat conductive and corrosion resisting material, such as copper, formed as a separate element or sub-assembly of the iron as a whole. Hence, such container may be readily removed and replaced for inspection, removal of deposits therein, or repair of the container.

The socket 32 in the water container 28 is shaped to receive a sub-assembly or unit 40 which includes a water separating portion 41, a steam conduit portion 42, a spacer stem 43, and a pressure relief device 44. The water separator is formed with walls 46 defining a groove-like space open at the bottom and formed with holes 47 through the end walls of the space, the side walls extending beyond the end walls for short distances to serve as guards in preventing splashing of water into the space between the walls 46. Steam rising from the water in the container 28 flows through the space between the walls at the bottom thereof and through the holes 47. The steam readily changes its direction of flow but any droplets of water carried by the steam impinge on the walls 46 and drop back into the body of water through the bottom opening from the space between the walls.

A steam passage 49 leads through the steam conduit portion 42 from the water separator space into a space in the spacer stem portion 43. Such spacer stem portion extends from the bottom of the water container 28 through the top thereof, and the upper end thereof is closed by a gasketed plug 50 threaded into the stem which is interiorly cylindrical with an enlarged upper portion forming a shoulder 51. The stem is preferably streamlined or has a pointed edge, as shown at 52 in Fig. 12, to avoid splashing of water when rearward movement of the iron causes forward movement of the water in the container, thus minimizing the entrainment of water in the steam rising into the water separator. The spacer stem 43 is designed to receive

a screw 54 with a passage therethrough to form a portion of the steam conduit. The end of the screw 54 is threaded into the hole through the sole plate and the head of the screw acts on the shoulder 51 in the spacer 43 when drawn up against a gasket 55 seated between the water container and the sole plate about the apertures therethrough.

A steam superheater and distributor plate 56 is mounted in the recess in the sole plate 20. The superheater and distributor plate 56 is preferably formed with concentric grooves therein or slots therethrough defined by an apertured central portion 57, a wall 58 concentric with the central portion and spaced therefrom, and a skirt portion 59. The plate central portion 57 has a well-like space 60 therein in registry with the passage through the screw 54 and has a notch 61 leading therefrom. The wall 58 is notched, as at 62, and the skirt 59 is notched, as at 63. The plate 56 is held firmly seated in the sole plate recess by screws 64 passing through the plate 56 and into the sole plate 20. The central aperture in plate 56 receives the end of the screw 54 so that the slot 60 therein registers with notch 61 when the head of screw 54 rests on spacer shoulder 51.

The superheater-distributor grooves or passages form a labyrinth through which the steam must flow to the exits 63 and in which the steam is heated before delivery between the smoothing surface of the iron and the textile being ironed. Steam is delivered by way of the conduit 49 and passes through the screw 54 to discharge through the space 60 and the notch 61 into the groove from which the steam may flow only through the notches 62 into the space within the skirt 59 and the steam flows from such space by way of the notches 63. It will be noticed that the notches 62 do not register with the notch 61 and that the notches 62 and 63 are not in registry. The steam therefore follows a tortuous path in contact with the heated plate 56, thus drying and superheating the steam before contact with the material being ironed. The notches 63 are located at points which experiment has shown as being the best positions for uniformly delivering the steam to the material being ironed. It will be understood that notches 62 and 63 are merely breaks in the edges of wall 58 and skirt 59 so that the superheated steam, which tends to remain in contact with the plate, may be caused to discharge therefrom at very slight pressure.

An opening is formed in the portion 44 of the unit sub-assembly 40 and is defined by a flange 67, an enlarged portion of the opening above the flange being interiorly threaded. A plate 68 of ductile material of low tensile strength, such as zinc, is seated on the plane upper surface of the flange 67. A plug 69 of annular shape is threaded into the hole and has a rib 70 which is knife-edged and bears on the plate 68 to seal such plate on the flange. The plate 68 is accordingly easily sealed on flange 67 but is readily frangible to relieve steam pressure above a predetermined value. If the steam pressure in the water container and steam generator 28 exceeds a predetermined limit, the plate 68 gives way to relieve such excess pressure, thus preventing injury to the user or damage to the water container.

The water container and steam generator 28 is enclosed in a shell 73 preferably in uniformly spaced relation to and conforming in contour substantially to the contour of such container. The interior surface of the shell may be coated

or the space between the container and shell may be filled with a heat-insulating material, if desired. Flow of heat from the water container-steam generator 28 to the shell is thus kept to a low value. The shell has no bottom wall and the edge 74 of the shell wall rests on the pads 23 of the sole plate. Hence, such edge is spaced from the sole plate along a major portion of its length, thus minimizing the flow of heat from the sole plate to the shell. The shell is provided with an aperture conforming in shape to and registering with socket 32 of the water container as well as with apertures for extension therethrough of the filling neck 29 and other apertures, for a purpose which will appear hereinafter.

The shell encloses a space to the rear of the water container 28 in which are located a thermostat, generally indicated at 76, and fully disclosed in U. S. Patent 2,405,869, issued to me on August 13, 1946, and a terminal block to be described. The thermostat is suitably mounted on the sole plate and is adjusted by a stem 77 extending through the shell and provided with a thumb-wheel 78 graduated to indicate different settings of the thermostat and marked to identify different textiles for which the different thermostat settings are suited. The terminal block comprises a metal frame 80 with a plate 81 extending from the side thereof for mounting on lugs 82 extending from the sole plate. A disc-like member 83 of electrical insulating and heat-resistive material, such as porcelain, is adapted to be retained in the frame and is formed with notches engaging with frame ears in a bayonet-type of lock. The terminal block serves as the connecting point for ribbon-like connectors 87 from the resistive element 21, the thermostat 76, and leads 84, to a source of electric current, such connections being by way of terminal bolts 85 extending through holes 86 in plate 81. If desired, the connectors 87 may be passed through slots 88 in the disc 83 before fastening by the bolts to others of the electrical conductors, the bolts 85 then being reversed, as may be seen by comparison of Figs. 9 and 14.

A handle 91 is mounted on the shell and has pads 92 and 93 at four points which are the only contacts of the handle on the shell, the handle being spaced from the other portions of the shell surface. The handle is attached to the shell, as by screws 94, into the sub-assembly 40 (see Fig. 2), and as by screws 95 (see Fig. 8). The handle is recessed to receive the steam conduit portion 42 of the unit 40 as well as the thermostat thumb-wheel 78 and the stem 77, the leads 84, and so forth. It will be seen that the handle has flanges 96 particularly adjacent the pressure relief portion 44 of the sub-assembly 40, the flanges being spaced from the shell so that steam escaping upon breakage of the plate 68 is readily vented but will not directly come into contact with the hands of the user of the iron. It will be seen that the rear end of the handle projects beyond the rear of the sole plate to serve as part of the support when the iron is placed in a vertical position. The portion of the handle 91 toward the rear of the iron has a channel-like space formed therein to receive the electric cord 84. Such cord extends from the terminal block 80, 81, through a hole in the shell 73 and in the handle, and into the handle space, and extends upwardly through such space, as indicated in Fig. 6, and projects from the handle through a sleeve 97 of suitable flexible material. The transmission of strains on the cord 84 to the terminal block 80, 81 is pre-

vented by clamping the cord in the handle space, as shown at 98. The handle mounting screws 95 and the cord in the handle space are covered against too ready access thereto by a plate 99 which may bear operating instructions and other data desired.

Immediately above the space within the shell for receiving the thermostat, a space is provided in the handle 91 for receiving the thermostat stem 77 and the thumb-wheel 78. The end of the stem 77 projecting through the shell 73 into the space in the handle, is threaded to receive a rectangular hublike member 105 which may be locked in any desired position on the stem thread by a nut 106. The stem is also provided with a flange 107, the purpose of which will appear hereinafter. A block 108 is fitted into the handle space in such manner as to leave only sufficient space for the thumb-wheel between the block and the handle. The block is formed with a passage therethrough in which the hub 105 may rotate and is provided with other passages for the flow of air therethrough for cooling purposes. The upper surfaces of the block 108 have an offset formed thereon to provide a bearing for the thumb-wheel which also bears in the handle, as indicated at 109. The thumb-wheel has a socket therein in which the hub 105 fits in sliding relation so that rotation of the wheel produces rotation of the stem and also allows vertical movement of the stem as required by its threaded connection with the thermostat structure. The block 108 is held in the handle by screws 110.

In assembling the iron, the thermostat stem is adjusted to produce opening and closing of the thermostat at several given temperatures suitable, for example, for rayon and silk textiles. The hub 105 is then threaded on the stem and is locked in such position that it will receive the thumbwheel 78 in the position shown in Fig. 9. The wheel is then turned to the "off" position at which the thermostat is open, and the splines of a ring 111 with a finger 112 projecting therefrom, and previously loose on the stem 77, are engaged with a splined surface on the stem in such position that the finger contacts one side of a limit stop 113 on the thermostat structure.

Two spaced lugs 116 are attached to the rear end of the shell as by clinching over tabs 117 thereon extending inside the shell. The lugs project farther rearwardly than the handle 91 and provide two points which are employed in connection with the end of the handle to stand the iron in vertical position. The lugs are preferably hollow and are provided with a plurality of holes 118 for the flow of air therethrough.

The steam superheater and distributor may also be made as shown in Figs. 16 and 17, in which a third wall is provided, thus lengthening the passage through which the steam must flow in contact with the plate and producing a higher degree of superheat. The third wall 121 defines another groove and is provided with notches 122 and 123 through which the steam discharges into the space adjacent the skirt 59 from which the steam escapes to the textile being ironed through the notches 63. For some uses even a higher degree of superheat may be desired in which case a further wall is provided and the notches in walls between central portion and the skirt are suitably rearranged.

Figs. 18 and 19 show a modified form of water separator having a plurality of groove-like spaces defined by the side walls 130, 131, 132, and 133, and the end walls 136 and 137. The steam enters

the separator by way of the holes 140 and 141 and impinges on the walls 132 and 133, respectively. The direction of flow of the steam is then changed so that the steam flows through the spaces between the walls 130-131 and 132-133, and impinges on the end walls 136 and 137. The direction of steam flow is then changed to pass through the holes 142 and 143 to cause another impingement of the steam on the walls 132 and 133 before the steam flows through the final space into the steam passage 49. Plugs 145 and 146 close holes made in walls 131 and 134 when drilling holes 142 and 143. It will be seen from the above that the direction of steam flow is changed a number of times, thus securing a number of impingements of water droplets on the water separator walls and securing a number of changes in direction of flow of the steam and the water droplets, all of which contributes to the effective separation of entrained water from the steam. The steam flow passage may be made even more tortuous if desired, particularly if a higher degree of superheat is desired. It will be understood that the degree of superheat obtained is a result of the coaction of the water separator and the steam superheater plate and that change in either of such elements affects the other.

It will be understood that the shapes of the several parts herein shown are merely illustrative and may be varied as desired to secure the best balance of the iron and the most acceptable appearance thereof. The material of the several parts, unless otherwise specified, will be any of those having the properties necessary to secure the functioning described, and the surface finish of any of such parts may be whatever is desired. The water separator and the steam super-heater and the resistance element used will be determined by the quantity of heat required to yield the desired quantity of steam at a given superheat and to keep the temperature of the smoothing surface of the iron at a desired value.

Although but one embodiment of the present invention has been illustrated and described, it will be apparent to those skilled in the art that various changes and modifications may be made therein without departing from the spirit of the invention or from the scope of the appended claims.

I claim:

1. An electric steam iron comprising a sole plate with an aperture therethrough to the smoothing surface thereof, a water container and steam generator mounted on the sole plate, and a structure mounted in and forming a part of the water container and steam generator and including a portion within the water container separating liquid water from steam and a portion conducting steam therethrough, the water separator portion defining at least one set of closely spaced walls extending substantially to the top thereof and forming a groove-like space

open at the bottom for return of water to the water container, at least one of said walls having an aperture therethrough adjacent the upper end of the space for the flow of steam therethrough and into the space for providing a change in the direction of steam flow.

2. An electric steam iron comprising a sole plate having an aperture therethrough to the smoothing surface thereof, a water container and steam generator mounted on the sole plate, and a structure mounted on and forming part of the water container and steam generator and including a portion within the water container separating liquid water from steam and a portion conducting steam therethrough, the water separating portion being formed with end walls and side walls extending beyond the end walls and defining a groove-like space open at the bottom above the surface of the water in and for return of water to the water container, the end walls having apertures therethrough adjacent the upper end of the space for the flow of steam therethrough and into the space, the extending end walls providing a change in direction of steam flow.

3. An electric steam iron comprising a sole plate with an aperture therethrough to the smoothing surface thereof, a water container and steam generator mounted on the sole plate, and a structure mounted in and forming a part of the water container and steam generator and including a portion within the water container separating liquid water from steam and a portion conducting steam therethrough, the water separator portion defining a plurality of sets of closely spaced walls extending substantially to the top thereof and forming groove-like spaces open at the bottom for return of water to the water container, said closely spaced walls having unaligned apertures therethrough adjacent the upper ends thereof for providing a change in direction of steam flow.

ALFRED WILD.
